UNITED STATES PATENT OFFICE.

ADOLPH F. RIETZEL, OF CHARLESTOWN, RHODE ISLAND, ASSIGNOR TO WALLACE H. ROWE, OF PITTSBURGH, PENNSYLVANIA.

REEL.

1,083,298.

Specification of Letters Patent.

Patented Jan. 6, 1914.

Application filed March 14, 1910. Serial No. 549,205.

To all whom it may concern:

Be it known that I, ADOLPH F. RIETZEL, a citizen of the United States, and a resident of Charlestown, in the county of Washington and State of Rhode Island, have invented certain new and useful Improvements in Reels, of which the following is a specification.

My present invention relates to the construction of reels such as used for holding and shipping barbed or other wire or for other purposes and more particularly relates to such reels when constructed of metal.

The object of my invention is to provide a reel which will require less metal than reels of types heretofore employed and which will therefore be cheaper to construct and lighter in weight but at the same time will be capable of carrying great weight without 20 danger of collapse.

The object is further to provide a reel which will be proof against fire and rough handling and which will take up less space in storage than is required by reels of constructions heretofore employed.

A further object is to so construct the reel that the process of electric welding may be employed in its manufacture, thus cheapening its cost of construction and providing an 30 integral structure whereby great strength is attained.

A still further object of the invention in its preferred form, is to make the various parts from sheet metal and to provide 35 various reinforcing devices to strengthen the same.

The invention consists in the novel construction of reel hereinafter more particularly described and then specified in the 40 claims.

In the accompanying drawings, Figure 1 is an end elevation of one form of reel constructed in accordance with my present invention and shows the parts before welding. 45 Fig. 2 is a side elevation of the same. Fig. 3 is a plan view. Fig. 4 is a plan view of the reel after the parts have been welded together. Fig. 5 is an end elevation of another form of reel constructed in accordance 50 with this invention.

The side members or arms of the reel each preferably consist of but a single plate or strip of metal 1 to which the body portion or drum of the reel is secured. The 55 strips or plates 1, forming the reel arms,

are preferably trough- or channel-shaped in cross-section and by preference formed by bending the longitudinal edges of strips or plates of sheet metal to form side flanges, thereby greatly stiffening the plates, although the arms might be otherwise formed if desired.

The plates or arms 1 are provided with an opening 2 through the base of the channel at or about the middle thereof and which provides for the insertion of the usual supporting spindle commonly employed to sustain the reel when winding or unwinding the wire. The body of the reel or the drum portion, upon which the wire is wound consists of a plurality of bars or lengths of metal disposed about the axis of the reel and welded at their ends to the arms 1.

Referring more particularly to Figs. 1 to 5 inclusive, the body portion consists of 75 lengths or plates of metal 3 having longitudinal troughs formed therein in any convenient manner. The troughs may extend the entire length of the plates 3 or, as shown, may stop short of the ends and the 80 members terminate at each end in a flat portion which is welded to the arms 1 in any desired manner. Preferably, the trough-shaped members or plates are secured by welding them to the side flanges of the arms 85 1 by means of welding projections or nibs of localized area 4 struck up from the abutting surfaces of the arms 1 and plates 3. The parts are assembled together with the 90 projections 4 in contact between suitable current carrying electrodes, the current passing from one to the other and pressure applied thereto to complete the weld, all as well understood by those skilled in the electric welding art. It will be understood that 95 I do not limit myself to any particular method of electrically welding the parts together and in utilizing welding projections to localize the area of initial contact it will be understood that they might be provided 100 in any desired way and might be formed on either or both of the parts to be welded.

In Figs. 1 and 2 the body portion is formed of two plates, one on either side of the arms 1 and each plate provided with 105 two parallel longitudinal troughs while in the form shown in Fig. 5 each trough is formed in separate plates or strips forming bars terminating in flat portions and secured to the arms as above described.

What I claim as my invention is:

1. In a metal reel, reel arms each consisting of a single channel-shaped strip of metal and a reel body comprising metal plates having longitudinal troughs formed therein and welded to the sides of said channel-shaped arms.
2. In a metal reel, reel arms each consisting of a single metal plate having side flanges and a reel body comprising metal plates having longitudinal troughs formed therein and welded by their face to the flanges of said arms.
3. In a metal reel, reel arms each consisting of a single metal plate having side flanges and a reel body comprising metal plates having longitudinal troughs and

welded by their face to the face of said flanges.

4. In a metal reel, reel arms each consisting of a single channel-shaped piece of metal and a reel body comprising a pair of plates welded to the sides of said channel-shaped arms, said plates being provided with longitudinally disposed parallel troughs formed therein.

Signed at Stonington in the county of New London and State of Conn. this 9th day of March A. D. 1910.

ADOLPH F. RIETZEL.
